UNITED STATES PATENT OFFICE.

JOHN T. SNELSON, OF ROCKY FORD, COLORADO.

MACHINE FOR IRONING COLLARS.

REISSUED

No. 921,906.

Specification of Letters Patent.

Patented May 18, 1909.

Application filed August 1, 1907. Serial No. 386,667.

To all whom it may concern:

Be it known that I, JOHN T. SNELSON, a citizen of the United States, residing at Rocky Ford, in the county of Otero and State of Colorado, have invented a new and useful Machine for Ironing Collars, of which the following is a specification.

This invention relates to machines for ironing turn down collars, and has especial reference to machines which will fold the collars, and at the same time smooth and finish the folded edges of the same.

The invention has for its object to provide an improved machine of this class that may be readily adjusted in order to vary the pressure exerted between the iron and the folding member.

The invention further has for its object to provide an improved machine of this class which will accommodate collars of different thicknesses and of any size.

With these and other objects in view, as will more fully hereinafter appear the invention consists in certain novel features of construction and arrangement of parts, herein-after fully described, illustrated in the accompanying drawings and particularly pointed out in the appended claims, it being understood that various changes in the form, proportions, size and minor details of the structure may be made without departing from the spirit or sacrificing any of the advantages of the invention.

In the accompanying drawings:—Figure 1 is a side elevation of a collar ironing machine constructed in accordance with the invention. Fig. 2 is a detail view of the drying tube. Fig. 3 is a detail view of the bearing 20.

Similar numerals of reference are employed to indicate corresponding parts throughout the several figures of the drawings.

The machine is provided with a suitable base 10 that may be mounted on top of a table or other support at any convenient height for the operator. Extending upward from the base are two standards 11 and 12 that support all of the working parts of the machine. At the top of the standards are arranged bearings for the reception of a horizontally disposed shaft 15 on which is mounted a loose pulley 16 that may be connected to the shaft by a clutch 17 of any ordinary construction. The shaft 15 is made in two sections that are connected together by a flexible section 18, and the forward end of the

shaft is inclined downward toward the front of the machine and carries a conical folder 19 that is arranged to engage the inner face of the collar, as more fully described hereinafter. 60 In the standard 11 is pivoted a bearing 20, the bearing being mounted on a pair of diametrically opposed screws 21, and this bearing forms a bearing for one end of a shaft 22, which also has a bearing in a slideable block 65 23 located between its ends and arranged to move vertically in a slot formed in the lower portion of the standard 12. The two shafts 15 and 22 are connected together by a belt 24 running over suitable pulleys on the shafts. 70 Arranged at the extreme forward end of the shaft 22 is a smoothing iron 26 of circular form and provided with a groove 27 to receive the bend of the collars, this groove being directly opposite the edge of the bending 75 cone 19. The iron is provided with an annular groove 28, against which a heating jet is directed from a gas pipe 29. The box 23 is pressed upward by means of a helical compression spring 30, that tends to force the 80 iron into contact with the cone, and maintain sufficient pressure on the collar for the purpose desired. At the top of the box is a ball 32 engaged by an adjusting screw 33, which may be turned for the purpose of 85 regulating the limit of upward movement of the iron. The stress of the spring 30 may be regulated by a screw 35 that extends through a threaded opening in the base and engages the pivoted lever 36, one end of which bears 90 against the lower end of the spring 30.

At one side of the front portion of the machine is arranged a drier comprising an outer steam heated tube 40 and an inner steam heated tube 41, the two tubes being 95 separated from each other by an annular space into which the collars are directed from the machine. The outer casing is supported in any suitable manner, and the inner drum or hollow tube is supported by a spider 100 42. The outer tube 40 is open at one point to permit the entrance of collars and the wall of the tube is deflected outwardly in the form of a plate 43 to which is secured the upper edge of a spring plate 44, this plate being designed to enter between the front and back of the collar, the front fold of the collar being disposed between the spring and the plate 43, while the rear fold is on the outer face of the spring, and is arranged to be engaged by a 105 feed roller 45. The roller 45 is formed of or covered with rubber or other yieldable ma-

terial and is mounted on a vertical shaft at the upper end of which is arranged a bevel gear 46. This bevel gear intermeshes with a bevel gear 47 on a horizontally disposed shaft 48 that is adapted to bearings formed in brackets 49 carried by the frame of the machine. The shaft 48 has at one end a belt wheel 50 that is driven by a belt 51 from a pulley 52 on the shaft 15, and the pulleys and gears are so proportioned that the roller 45 will act as a feeder to draw the collars through the machine and force them into the collar drying space between the tubes. After each collar is delivered, it is forced down by a depressing ring 53 that is mounted on a suitable spring 54, that tends normally to hold it in elevated position. The ring has an operating handle 55 that extends out through a slot in the tube.

20 In using the machine, the collars are introduced between the cone and the iron, and are properly creased and bent, the cone engaging the inside of the collar, while the iron smooths and finishes the collar at the fold line. The collars are fed one by one into the drying tube, and after the entrance of each collar the depressing ring 53 is pushed down, the collars being successively discharged from the bottom of the tube perfectly dry 30 and ready for wrapping.

I claim:—

1. In a machine of the class described, a

horizontal shaft; a grooved iron on the outer end of said shaft; a pivotal bearing in which the inner end of said shaft is mounted, a slotted bracket intermediate of the ends of said shaft, a bearing block carrying the shaft and arranged for vertical movement in said slotted bracket, an adjustable spring bearing against the under side of said block, an adjustable ball stop on the upper side of said block; and a revoluble collar folding cone, located at an angle to the grooved iron. 35

2. In a machine of the class described, a horizontal shaft; a grooved iron on the outer end of said shaft; a pivotal bearing in which the inner end of said shaft is mounted, a second bearing for said shaft intermediate of its ends, and consisting of a slotted bracket, a vertically movable block in said bracket 50 through which said shaft extends; a spring bearing against one side of said block a lever with adjusting screw supporting said spring, an adjusting screw on the opposite side of said block, and a revoluble cone located at 55 an angle to said grooved iron.

In testimony that I claim the foregoing as my own, I have hereto affixed my signature in the presence of two witnesses.

JOHN T. SNELSON.
